No. 787,682.

PATENTED APR. 18, 1905.

F. W. LANGEHENNIG.

CAR CONSTRUCTION.

APPLICATION FILED NOV. 21, 1904.

FIG. I

FIG. II.

Attest:

M. J. Smith
F. W. Langehennig

Inventor:

F. W. Langehennig

By Thos. H. Pro
Atty.

UNITED STATES PATENT OFFICE.

FREDRICK W. LANGEHENNIG, OF ST. LOUIS, MISSOURI, ASSIGNOR TO ST. LOUIS CAR COMPANY, OF ST. LOUIS, MISSOURI, A. CORPORATION.

CAR CONSTRUCTION.

SPECIFICATION forming part of Letters Patent No. 787,682, dated April 18, 1905.

Application filed November 21, 1904. Serial No. 233,704.

To all whom it may concern:

Be it known that I, FREDRICK W. LANGEHENNIG, a citizen of the United States, residing in the city of St. Louis, in the State of Missouri, have invented certain new and useful Improvements in Car Construction, of which the following is a full, clear, and exact description, reference being had to the accompanying drawings, forming part of this specification.

My invention relates to a railway-car construction; and, briefly stated, it consists in the production of composite side sills in a car including as parts thereof insert tie-plates that extend upwardly from the tops of the sills and constitute the members by which the sides of the car, including the posts, are united to the side sills.

Figure I is a top or plan view of the under-frame of a railway-car with my improvement incorporated therein. Fig. II is a transverse section of my underframe with the lower portion of one of the car sides shown built up.

A designates the intermediate sills of a car underframe, and B the floor mounted thereon, for neither of which any invention is herein claimed. The side sills of the underframe consist of the following parts: 1 designates metal channel-beams placed together in pairs and having their flanges projecting in opposite directions, and 2 designates wooden sill members that are seated between the flanges of the channel-beams, to which they are connected by binding-bolts 3 extending transversely through said parts.

4 designates metal insert tie-plates positioned between the inner opposing faces of the metal channel-beams 1 and are held in such position by the binding-bolts 3. These tie-plates are of sufficient width to permit of the plates extending upwardly above the tops of the sill channel-beams, as seen most clearly in Fig. II, and each tie-plate is provided at intervals corresponding to the spacing of the side posts of the car with bolt-holes 5.

6 designates one of the truss-planks which are located at the inner sides of the extended portions of the tie-plates 4 and rest upon the innermost sill channel-beams, and 7 is one of the seat-rails in which the side posts of the car are set, these seat-rails being located upon

the outermost sill channel-beams and occupying positions at the sides of the tie-plates opposite the locations of the truss-planks.

8 is one of the side posts, the lower ends of 55 which rest upon the seat-rails 7 and are fitted to the tie-plates 4. These posts, their seat-rails, and the truss-planks 6 are all connected to the tie-plates by binding-bolts 9, that pass through said parts and through the bolt-holes 60 5 in said plates.

10 designates the side sheathing, and 11 the inner paneling, which are respectively applied to outer and inner sides of the posts 8, the former extending downwardly to the bottoms of the side sills and the latter resting upon the truss-planks 6.

The construction herein described produces an extremely rigid connection between the side posts of the car and the side sills, due to 70 the use of the tie-plates 4, by which said parts are connected, thereby making it possible to dispense with the usual trusses common in car construction by which the parts of the under-frame of a car are stayed.

I claim as my invention—

1. In a car construction, the combination of side sills, insert tie-plates positioned between said sills and extending upwardly therefrom, and posts secured to said tie-plates, substantially as set forth.

2. In a car construction, the combination of side sills having channel-beams as members thereof, insert tie-plates interposed between said channel-beams and extending above the 85 tops of said beams, and posts secured to the extended portions of said tie-plates, substantially as set forth.

3. In a car construction, the combination of side sills, insert tie-plates positioned in said 90 sills and extending above the tops of the sills, truss-planks and seat-rails surmounting said sills at opposite sides of said tie-plates, posts seated upon said seat-rails alongside of said tie-plates, and means for connecting said 95 truss-planks, seat-rails and posts to said tie-plates, substantially as set forth.

FREDRICK W. LANGEHENNIG.

In presence of—

M. C. MURPHY,
ARTHUR DIEKMANN.
